[57] CLAIM

The ornamental design for a conveyor pallet, substantially as shown and described.

DESCRIPTION

FIG. 1 is a top plan view of a conveyor pallet showing my new design;

FIG. 2 is an end elevational view thereof, the opposite end elevational view being a mirror image of that shown;

FIG. 3 is a side elevational view thereof, the opposite side elevational view being a mirror image of that shown;

FIG. 4 is a bottom plan view thereof; and

FIG. 5 is a sectional view thereof, taken along the line 5—5 of FIG. 1.

FIG. 1

FIG. 2

FIG. 3

FIG. 4

FIG. 5
